Primary Examiner — Samantha Q Lawrence

(57) CLAIM

The ornamental design for an ear cleaner, as shown and described.

DESCRIPTION

FIG. 1 is a front elevational view of an ear cleaner showing my new design, the rear elevational view being mirror image thereof;

FIG. 2 is a left side elevational view thereof, the right side elevational view being mirror image thereof;

FIG. 3 is a top plan view thereof;

FIG. 4 is a bottom plan view thereof;

FIG. 5 is a perspective view thereof;

FIG. 6 is another perspective view thereof; and,

FIG. 7 is a perspective view of the ear cleaner shown with the cap removed for ease of illustration.

The broken lines in the drawings depict portions of the ear cleaner that form no part of the claimed design.

1 Claim, 7 Drawing Sheets
